UNITED STATES PATENT OFFICE

163,069

BOTTLE HOLDER

Grant W. Roberts, Bedford, Va.

Application September 12, 1950, Serial No. 12,152

Term of patent 3½ years

(Cl. D83—8)

To all whom it may concern:

Be it known that I, Grant W. Roberts, a citizen of the United States, residing at Bedford, in the county of Bedford and State of Virginia, have invented a new, original, and ornamental Design for a Bottle Holder, of which the following is a specification; reference being had to the accompanying drawings forming a part thereof.

Figure 4 is a view in perspective of the holder and attaching strap which is shown for illustrative purposes only and is adapted to secure the holder to the seat of a vehicle.

I claim:

The ornamental design for a bottle holder, as shown and described.

GRANT W. ROBERTS.
